UNITED STATES PATENT OFFICE.

FREDERICK A. WILKE, OF RICHMOND, INDIANA.

DESIGN FOR A REFRIGERATOR.

SPECIFICATION forming part of Design No. 31,203, dated July 11, 1899.

Application filed June 16, 1899. Serial No. 720,857. Term of patent 14 years.

To all whom it may concern:

Be it known that I, FREDERICK A. WILKE, residing at Richmond, in the county of Wayne and State of Indiana, have invented and produced a new and original Design for a Refrigerator, of which the following is a specification.

The object of my invention is to provide a new design for refrigerators, the features of which are more fully set forth in the description of the accompanying drawing, making a part of this specification, in which—

The drawing represents a perspective view of a refrigerator with my design applied.

15 My design embraces the refrigerator A, with the outside finishing-lines arranged in rectangular checker-work B or block-like squares.

C represents the doors, the margins being formed of longitudinal strips D d, inside 20 of which is applied the rectangular checker-work B. At the intersection of the checks are ornamental bolt-heads H, symmetrically arranged at the junctions of the checker-lines.

E represents the hinges and hinge-plates of 25 the doors, which intercept the block or checker work, as shown.

F represents the door-fastenings.

G represents a projected molding-base. G'

represents raised corner finishing-pieces. The face of the base is overlaid with the 30 checker or block work. The corners of the refrigerator are also provided with raised finishing-pieces. The faces inside of the corner-pieces are overlaid with the block or checker work B. All intersecting checker-lines are 35 provided with the ornamental heads H.

I represents the interior of the receptacle, which is overlaid with the block or checker work. This gives the same beautiful appearance when the doors are opened or when transparent paneling is applied to the door-frame, as shown, for the lower receptacle.

The body of the refrigerator is of tessellated form, variegated, with the door and corner strips and the ornamented bolt-heads at the 45 intersecting lines.

Having described my invention, I claim—

The design for a refrigerator substantially as herein shown and described.

In testimony whereof I have hereunto set 50 my hand.

FREDERICK A. WILKE.
